US00D820735S

(12) **United States Design Patent** (10) **Patent No.:** **US D820,735 S**
(45) **Date of Patent:** **** Jun. 19, 2018**

(54) **LOAD CUSHION**

(71) Applicant: **Hendrickson USA, L.L.C.**, Itasca, IL (US)

(72) Inventors: **Shawn D. Noble**, Naperville, IL (US); **Matthew J. Van Meter**, Plainfield, IL (US)

(73) Assignee: **Hendrickson USA, L.L.C.**, Itasca, IL (US)

(**) Term: **15 Years**

(21) Appl. No.: **29/561,419**

(22) Filed: **Apr. 15, 2016**

Related U.S. Application Data

(63) Continuation of application No. 29/518,936, filed on Feb. 27, 2015, now Pat. No. Des. 764,361, and a continuation of application No. 14/500,106, filed on Sep. 29, 2014, now Pat. No. 9,604,517.

(57) **CLAIM**

The ornamental design for a load cushion, as shown and described.

DESCRIPTION

FIG. 1 is a perspective top and left side view of a load cushion, having the inventive design;

FIG. 2 is a bottom view thereof;

FIG. 3 is a top view thereof;

FIG. 4 is a left side view thereof;

FIG. 5 is a right side view thereof;

FIG. 6 is a front view thereof; and,

FIG. 7 is a rear view thereof.

The broken lines in the drawings are for the purpose of illustrating portions of the load cushion that form no part of the claimed design.

1 Claim, 4 Drawing Sheets
